SYSTEM AND APPARATUS FOR FLOWING
WELLS

Jeddy D. Nixon, Houston, Tex., assignor of one-half to Wilson Supply Company, Houston, Tex., a corporation of Texas

Application March 10, 1941, Serial No. 382,489

25 Claims. (Cl. 103—232)

This invention relates to new and useful improvements in systems and apparatus for the flowing of wells.

This application is filed as an improvement and a continuation in part of my co-pending applications, Serial No. 365,024, filed November 9, 1940, and Serial No. 377,603, filed February 6, 1941.

One object of the invention is to provide an improved system and valve that serves the same purposes and functions as that set forth in my co-pending application, Serial No. 365,024, filed November 9, 1940, and is an improvement thereon in action, structure and operation.

An important object of the invention is to provide an improved fluid inlet valve which is so constructed that the valve stem is a full floating type, whereby its movement or action is unimpeded, which makes it a free acting valve stem.

A further object of the invention is to provide an improved fluid inlet valve so arranged that the valve may be locked against and released for actuation, whereby when said valve is released, the same is fully pressure responsive or automatic in operation to the well fluid and the lifting fluid and substantially all friction is eliminated to insure the proper operation of said valve.

It is pointed out that the larger portion of all wells fluctuate and vary in the quantity of fluid produced, the constituency or composition of the produced fluid and the rate at which the wells produce their fluids. Also, the components or composition of the well fluid, as well as the amount of fluid allowed to be produced, are factors in determining the various producing conditions encountered. In producing fluid from a well with a pressure or a lifting fluid, the lifting fluid is stored or maintained in an annular space, usually the well casing, and the amount of pressure of the lifting fluid maintained generally determines the quantity of well fluid that may be lifted. The length of the flow line from the usual casing head to the storage tanks or other suitable disposal determines the back pressure that is placed on the fluid traveling through said flow line and in said well tubing. The longer the flow line is, the greater the back pressure that is set up and this back pressure affects to some extent the lifting of the well fluid.

It is possible with applicant's invention to vary the pressure of the lifting fluid maintained in said well casing to control the amount of the fluid lifted, the intervals at which it is lifted and the velocity of the lifted fluid. However, any change in the weight of the well fluid due to

variance in the composition of said fluid does not affect the operation of the inlet valve nor the surface control mechanism. Although, the different constituents of the well fluid encountered in various installations will affect the setting of the surface control mechanism.

It is also possible to change the pressure differential of applicant's fluid inlet valve to obtain the desired opening pressure in order to increase or decrease the velocity of the lifted body or "slug" of well fluid flowing up the tubing and through the flow line. Furthermore, by changing the opening or operating pressure of the surface control apparatus, different weights and lengths of slugs may be satisfactorily handled, as well as the different back pressures that are set up by the various lengths of flow lines and other operating conditions.

Still another object of the invention is to provide an improved fluid inlet valve that may be so arranged that adjustments may be made to obtain various opening pressures in order to increase or decrease the velocity of the lifted well fluid, whereby the opening pressure may be predetermined and set to handle the well fluid in accordance with the well conditions of the particular installation.

A still further object of the invention is to provide an improved control apparatus which may be so regulated that the opening pressure thereof may be varied to handle different weights and/or lengths of lifted bodies of well fluids and the different back pressures encountered, whereby further producing conditions encountered may be satisfactorily solved.

Another important object of the invention is to provide an improved control apparatus for the system which is more flexible in operation and more positive in control, whereby the mechanism may be regulated as desired.

Still another object of the invention is to provide an improved control apparatus that may operate to lock said inlet valve on one pressure and may operate to unlock or release said valve on a different pressure, whereby said apparatus may be adjusted for the two different operating pressures and these pressures may be predetermined to handle the various producing conditions encountered.

A further object of the invention is to provide an improved surface control mechanism which may be changed or adapted to meet various operating conditions and which will control the actuation of an operating element or bar, as shown in my above-mentioned, co-pending ap-

plication, or which may control a different type of operating element.

A construction designed to carry out the invention will be hereinafter described, together with other features and objects of the invention.

The invention will be more readily understood from the following specification and by reference to the accompanying drawings, in which an example of the invention is shown, and wherein:

Figure 1 is a view, partly in elevation and partly in section, showing the upper portion of a well with a well fluid lifting apparatus connected thereon, constructed in accordance with the invention;

Fig. 2 is a continuation of Figure 1, partly in elevation and partly in section, showing the lower portion of the well casing and the tubing string with fluid inlet valves, constructed in accordance with the invention, mounted in said tubing and the operating device therefor;

Figure 3 is plan view taken on the line 3—3 of Figure 1;

Figure 4 is a vertical, sectional view of a portion of the control mechanism;

Figure 5 is a longitudinal, sectional view of one of the inlet valves, showing the valve closed and released and in position for automatic operation;

Figure 6 is a similar view, showing the valve opened for the admission of fluid;

Figure 7 is a longitudinal, sectional view of the valve, showing said valve being closed and being fastened against automatic actuation.

Figure 8 is a horizontal, cross-sectional view taken on the line 8—8 of Figure 5;

Figure 9 is a similar view taken on the line 9—9 of Figure 5;

Figure 10 is a horizontal, cross-sectional view taken on the line 10—10 of Figure 6;

Figure 11 is a similar view taken on the line 11—11 of Figure 7;

Figure 12 is a horizontal, cross-sectional view taken on the line 12—12 of Figure 7;

Figure 13 is a view, similar to Figure 4, showing a modified form of the control mechanism;

Figure 14 is a detail view of the regulator valve body;

Figure 15 is a view, partly in section and partly in elevation, showing the upper portion of a well illustrating a modified actuating mechanism for this form of the invention;

Figure 16 is a longitudinal, sectional view of a fluid inlet valve operated by this form of the invention, showing the valve closed and released and in position for automatic operation; and

Figure 17 is a similar view, showing the valve closed and fastened against automatic actuation.

In the drawings, the numeral 20 designates the usual well casing which may be placed in the well bore in any suitable manner and in accordance with the conditions present at the particular well, which it is desired to automatically flow. A suitable casing head 21 is mounted on the upper end of the casing 20 in accordance with the practice now in common use, and this head is provided with a pressure fluid inlet pipe 22 in which a cut-off valve 23 is connected. A single string of well tubing 24 is suspended or hung in the casing head 21 in any suitable manner and extends above said head, so that a T 25 may be connected therein. A well fluid discharge pipe 26 leads from the T and has a cut-off valve 27 connected therein.

In Figure 2, I have shown the tubing string 75

24 extending below the casing string 20 into the well shot hole S and having a perforated bull plug or strainer 28 screwed onto its lower end, but it is to be understood that the tubing may be terminated at any desired point and its relation to the lower end of the casing may be varied to suit the different well conditions encountered. It is customary to sometimes perforate the casing to admit the well fluid from the formation closed off by said casing, as well as to use liners and elongated screens. Any of these devices may be employed in connection with the invention, as well as a suitable packer or seal-off device 29, if desired or necessary for a particular installation.

In the tubing string 24 (Figure 2), one or more elongated flow valve bodies or nipples 30 may be mounted at any desired elevation. The number and the spacing of the valves used depends on the conditions and circumstances surrounding each well, as well as the use or requirement of any other flow equipment. It is customary to connect these valves in said tubing 24 at different elevations, using the uppermost valve or valves as a kick-off valve; however, it is within the scope of the invention to use a single valve as both a kick-off valve and a flow or lifting fluid inlet valve.

The elongated, cylindrical valve body 30 is provided on its upper end with a co-axial, reduced, externally screw-threaded pin 31 and with a similar pin 32 depending from its lower end. A cylindrical collar 33 is formed with an internally screw-threaded box 34 on its lower end for engaging and receiving the threaded pin 31 and a similar box 35 is formed on its upper end for receiving the externally screw-threaded pin 36 of said tubing 24. A similar collar 37, having an internally screw-threaded box 38 on its upper end, engages the threaded pin 32 on the lower end of said valve body 30. This collar 37 also has an internally screw-threaded box 39 on its lower end for receiving the externally screw-threaded pin 40 on the upper end of a section of tubing 24. It will be seen in Figures 2, 5, 6, 7, and 8, that by means of the collars 33 and 37 said flow valves 30 may be connected into said tubing string 24 wherever desired, either in place of the usual connecting collars of said tubing string, or if desired, any of the tubing joints or sections may be cut and threaded for receiving the boxes 35 and 39 of the collars 33 and 37 respectively. A suitable sealing ring 41 is placed on each pin 31 and 32 for receiving the abutting edge of the collars 33 and 37. These rings are preferably of a soft metal, such as brass, but any material suitable for the purpose may be used.

The body 30 has an axial bore 42 extending therethrough, which is smaller in diameter than the bore of said tubing string, and the pins 31 and 32 are beveled at 43 at each end of the bore 42, so as to guide tools and other appliances into said bore. In order to provide ample flow space through said valve bodies 30, a pair of elongated ducts 44 are provided longitudinally of the body on each side of the bore 42 thereof, as is best shown in Figures 5 to 12 inclusive. One side of the body is cut out to form a vertical, external recess 45 and a portion of this recess is connected to said bore 42 by an elongated channel 46. It will also be noticed that the ducts 44 and the channel 46 are placed substantially equidistantly around said bore 42, although the exact location thereof is not material to the

proper operation of said valve, with the exception of the channel 46.

An upright valve casing or housing 47 is mounted in this recess 45, so as to engage snugly between the shoulders 48 formed at the lower and upper ends of said recess. This valve housing 47 may be secured in the recess in any suitable manner, so that it may be removed, if necessary. It is common practice to bolt such structures, and the valve housing may be bolted to the valve body 30 by bolts 49 and these bolts are removed when it is desired to disconnect said housing 47. This housing, as shown in Figures 8, 9, 10, 11 and 12, may be given a nearly semi-circular shape and has an inlet chamber 50 at its lower end provided with radial perforations 51, whereby the well fluid or the lifting fluid from said well casing 20 may freely enter said chamber. The top of this chamber is formed by a transverse partition 52 extending across said valve housing, above which partition overhangs an ear 53 formed integrally with said valve housing 47.

The lower end of said housing is closed and provided with a screw-threaded and counter-bored opening 54 for receiving a plug 55, having an axial bore 56 extending therethrough. The partition 52 is provided with a vertical port 57 extending therethrough and the lower end thereof is suitably beveled to form a ground valve seat 58 to co-act with a valve head or member 59 mounted on the lower portion of a valve stem 60. The lower end of said valve stem, below the valve head 59, telescopes within the bore 56 of said plug 55. The upper portion of said stem extends up through the port 57 and into the ear 53, which forms a guide therefor. A second ear 61 overhangs the first ear 53 and is spaced therefrom to serve also as a guide for said stem.

The upper end of said valve stem is reduced to form a pilot pin 62 that telescopes into a socket 63 in a cap nut 64, which is screwed into the upper end of said valve housing 47. At the lower end of the pilot pin 62, the valve stem 60 is formed with a shoulder 65 for receiving a collar 66, which supports the lower end of a coiled spring 67; the upper end of this spring engages the underside of the nut 64. This spring is a relatively light one and is under a moderate compression. Just below the shoulder 65, the valve stem is formed with screw-threads 68 for receiving a stop nut or collar 69. This collar is provided with a set screw 70 (Figures 5, 6, 7 and 10) which engages in a key groove 71 in the valve stem 60, whereby said collar is held against rotation.

A sleeve 72, slidably mounted on the valve stem 60, has its upper end bearing against the collar 69. The lower end of the sleeve 72 is provided with a reduced, depending skirt 73 and it will be noticed in Figures 5, 6 and 7, that this sleeve 72 slides within the ear 61 and that the lower portion of this skirt 73 slides within said ear 53. A coiled spring 74 is confined between the lower edge of the sleeve 72 and the upper side of said ear 53 around said skirt 73. This spring is considerably heavier than the spring 67 and is under a greater compression, so as to force said sleeve upwardly into engagement with said stop collar 69 and to hold the valve head 59 on its seat 58.

The sleeve 72 is provided with diametrically opposite slots 75 which receive the yoke 76 of a bell crank lever 77, as is best shown in Figures

5, 6, 7, 8 and 9. The lower end of the lever 77 is pivoted on a pin 78 journaled in a slot 79 formed in the wall of the housing 47. The upper end of the lever 77 has a small roller 80 journaled therein. When the bore 42 of the valve body 30 is unobstructed, as in Figures 7, 11 and 12, the roller 80 on the lever 77 is free to swing through the channel 46 into said bore and this will be its position when the valve is closed; the spring 74 being under sufficient compression to raise the sleeve 72 and swing the lever 77. It will also be noticed from these figures, that the roller 80 extends through the channel 46 out into the bore 42, where it may be engaged by a cylindrical, actuating member or bar 81 when the same is in the bore 42, as shown in Figures 5, 6 and 8.

As hereinbefore pointed out, one of the objections to the ordinary automatic valve, which is employed for admitting lifting fluid to the well tubing, is that there is no positive way of controlling the opening and closing of said valve and particularly the closing of the same. It will be obvious that when the valve is closed (Figure 7) and the sleeve 72 is elevated so as to engage the collar 66, the spring 74 will not be under as great a compression as it will be when the lever 77 is swung outwardly and said sleeve moved downwardly from said collar, as shown in Figures 5 and 6. When the lever 77 is in the position shown in Figure 7, the valve is fastened or held against operation; whereas, when the lever is swung outwardly and the sleeve moved downwardly, as shown in Figure 5, the valve is released for automatic or pressure differential operation.

In order to fasten and release the valve, a suitable operating device must be provided for the lever 77. I have illustrated the actuating bar 81 which has a snug, sliding fit in the bore 42 of the valve body 30. The ends of this bar are beveled at 82, so that it will freely enter the valve body, to facilitate its passage up and down through the tubing, and so that said roller 80 may ride upon the bar 81. This bar is suspended by a wire line or other flexible connection 83 and has hanging from its lower end a rod 84, which supports a weight bar 85, and this weight bar co-acts with the bar 81 in holding the wire line 83 taut, as well as assuring a proper lowering of said bar. The upper and lower ends of the weight bar 85 are beveled at 86 for the same purposes and reasons as the bar 81. Any suitable means may be employed to actuate the wire line 83 to raise and lower the operating bar 81. When said bar is raised to the position shown in Figure 7, the lever 77 will be freed and permitted to swing through the channel 46 into the bore 42. In this position the valve will be fastened against operation.

When the operating bar 81 is lowered, the lower tapered face 82 engages the roller 80 and as the lowering is continued, the lever 77 is swung outwardly, whereby its yoke 76 is swung downwardly. The downward swing of the yoke 76 slides the sleeve 72 downwardly on the valve stem 60, whereby said sleeve is moved away from the stop collar 69 and further compresses the spring 74, bringing the parts to the position shown in Figure 5. In this position the valve is released and ready to be operated. This valve head 59 will be opened quickly when a pressure differential is built up by the hydrostatic head of oil or well fluid standing in the tubing 24, combined with the expansive force of the upper

spring 67, and when this pressure becomes sufficient to overcome the force of the lifting fluid exerted underneath said valve head 59, said valve head 59 and valve stem 60 will be moved downwardly until the collar 69 engages the upper edge of the sleeve 12, as shown in Figure 6.

Attention is called to Figures 5, 6 and 7, in which it will be seen that an annular recess or chamber 87 is cut in the wall of the bore 42 and that the lower edge of this recess is substantially even or on a line with the lower edge of the channel 46 and the upper surface of the partition 52. This recess 87 is provided so that the fluid flowing through the port 57 may readily flow around the weight bar 85 or operating bar 81 and into the ducts 44, whereby an even distribution of lifting fluid around said bar is obtained.

In the preferred form of operation, the casing 20, above the well fluid level standing therein, is filled with a lifting fluid which is constantly maintained under a head pressure sufficient, when admitted to the tubing, to elevate the body of well fluid which is picked up thereby and carried to the top of the tubing. It is pointed out, that by this arrangement, the casing and the inlet chamber or chambers 50 of the valve housing 47 is at all times maintained full of lifting fluid under the aforesaid pressure; and thus, when the valve head 59 is opened, the lifting fluid will be admitted immediately in such volume and under such pressure, as to pick up the well fluid standing above the valve in the tubing and carry it to the top thereof at a sufficient velocity to prevent slippage, or prevent the lifting fluid from channelling through the well fluid. In order to permit the lifting fluid to freely enter the ducts 44 of the valve 30, the channel or manifold 87 will lead the admitted fluid from said housing 47 to said ducts. Of course, if the well fluid level has not been lowered in the casing to the valve being opened, the well fluid will flow from said casing through said chamber 50, into said bore 42 of said opened valve 30, until the lifting fluid reaches this valve. None of the valves can be opened until the operating bar 81 or weight bar 85 swings the roller 80 outward and a sufficient column of well fluid is in the tubing to exert a greater weight or pressure differential over the pressure of the lifting fluid.

For raising and lowering the wire line 83, the control mechanism shown on the surface of my co-pending application, Serial No. 365,024, filed November 9, 1940, may be used, or the control mechanism I have shown in Figures 1 and 4 may be used, or any other mechanism desired. The control mechanism I have shown in these figures is enclosed in a water-proof, dust-tight housing 88 having a suitable cover or door 89 mounted thereon, which housing is mounted on an upright stand or pipe 90 for supporting the same. A pipe 91 having a suitable manually operated gate valve 92 therein leads from a T 93 in said lifting fluid supply line 22 to a threaded box 95 on the underside of a valve body 94 in said housing. This valve body 94 comprises the lower portion of a supply or regulator valve A and has a short pipe 96 extending from a threaded box 97 therein leading across the bottom of the housing to a threaded box 98 of the valve body 99, which comprises the lower portion of a feed or motor valve B. This valve B is located approximately at the center of the bottom of the housing 88. A continuation 100

of the pipe 96 extends from a threaded box 101, preferably diametrically opposite the box 98, across the bottom of said housing to a threaded box 102 of a valve body 103, which is the lower portion of a release valve C. The valves A, B and C are of the spring-loaded, diaphragm type and very similar in operation and construction to the valves shown in my fluid lift Patent No. 2,171,478, and above mentioned applications.

- 10 The valve body 94 of the regulator valve A is provided with an internal transverse partition 104 having a threaded port or bore 105 extending therethrough into which is threaded a removable metering or valve seat bushing 106.
- 15 The third threaded box or inlet port 107 of said valve body is suitably closed by a plug 108. The upper portion of said valve body is formed with an externally screw-threaded, upstanding boss 109 for receiving an internally screw-threaded cap 110. This cap 110 clamps a suitable stuffing box assembly 111 containing the usual packing 112 and follower block 113 with a tightening or retaining cap 114 thereon.
- 20 The locking cap 110 has a pair of upright arms 115, preferably diametrically opposite each other, which are connected at their upper ends to a piston chamber 116 and this chamber 116 has a radially extending, external flange 117 formed on its upper edge. A concavo-convex annular cap or crown 118 is mounted on the piston chamber and this cap is provided with an outwardly directed flange 119, similar to the flange 117, on its perimeter. These flanges 117 and 119 are clamped together by a plurality of bolts 120 and nuts 121 for gripping and clamping a diaphragm disk 122 therebetween. It is pointed out that a diaphragm actuating chamber 123 is formed above said diaphragm within said cap 118. This diaphragm is provided with an axial opening so that the upper end of a piston rod or valve stem 124 may extend therethrough, in order that said diaphragm and a flat circular piston 125 mounted therebeneath on said valve stem may be securely connected together by a nut 126 engaging the threaded upper end of said valve stem on the upper side of said diaphragm 122; whereby said diaphragm, said piston 125, and said valve stem 124 are clamped together and moved as a unitary structure.
- 25
- 30
- 35
- 40
- 45

- 50 It will be noticed in Figures 4 and 13, that a pair of the bolts 120', preferably diametrically opposite each other, are elongated so that, intermediate the ends thereof, an adjusting nut 127 may be mounted thereon. These nuts 127 adjustably support an elongated web member 128 whereby, upon the rotation of said nut 127, this web member may be raised or lowered as desired. A locking nut 129 is threaded on each bolt 120' above the web member 128 in order to clamp and lock said web member 128 in its adjusted position. A suitable coiled spring 130 is interposed between and bears against the upper surface of said web member 128 and the lower surface of said piston 125, so that an upward tension or thrust is placed or exerted upon said piston, said valve stem 124 and said diaphragm 122. Thus, it will be apparent that by adjusting said nuts 127 and 129, this tension is regulated and may be increased or decreased as is needed.
- 55
- 60
- 65
- 70

The lower end of said valve stem 124 depends or extends down within the valve body 94 to within a relatively short distance of the removable valve seat 106. This valve stem is tubular and formed with an axial bore or passage 131

extending entirely through said stem, so that fluid may flow through said valve stem from one end to the other. The lower portion of said bore 131 is counterbored at 132, in order to provide an entrance or admission chamber. A small, annular dart or foot piece 133 is positioned at the lower end of said valve stem within said counterbore 132 and has a conical valve tip or face 134 on its lower end and an upstanding, short, cylindrical pin 135 on its upper end extending up into the admission chamber or counterbore 132. This pin 135 has a loose fit within the lower portion of said counterbore 132 and the upper end of said pin abuts the lower end of a small coiled spring 136, that exerts a slight tension downwardly on 15 said dart 133. A small hole or opening 137 (Figure 14) is provided within the wall of said valve stem 124, adjacent the lower end of said valve stem, for providing additional communication between said counterbore 132 and the outside of said valve stem within said valve body 94. There is sufficient clearance around the pin 135 for the free flow of pressure fluid therearound and through the hole 137, so that fluid may readily flow into or out of said bore 131 of said valve 20 stem 124.

The replaceable valve seat bushing 106 has an axial bore 138 extending therethrough, the upper end of which is formed with a ground tapered seat to receive the conical valve tip 134, so as to close said passageway through said bushing. Attention is called to the fact that when pressure fluid enters said valve body 94 from said pipe 96, through said vertical passageway 138, said dart normally being in its lower or seated position after a reduced pressure has been built up in said pipe 96 and valve body 94 above the partition 104, said pressure fluid will engage and lift said dart 133 against the tension of said spring 136, as well as lift said valve stem 124 to open said regulator valve A to admit pressure fluid therethrough. This pressure fluid admitted through said passageway 138 will flow into the valve body 94 above the partition 104, as well as into said counterbore 132, both through said hole 137 and around said pin 135 of said dart. Then said pressure fluid will flow through said bore 131 of said valve stem 124 and out the upper end thereof, on top of the diaphragm 122 into said diaphragm actuating chamber 123 within the cap 118. In accordance with the setting of the spring 130, this pressure fluid flowing through the passageway 138 will be reduced to whatever pressure it is desired to maintain in the control mechanism. This pressure may be reduced or increased as desired by adjusting the nuts 129. This pressure fluid also will flow through the pipe 96 into the valve body 99 below a transverse partition 139 extending thereacross, similar to the partition 104.

A gauge 140 is screwed into the upper side of said cap 118 and extends through said cap, so that the reduced pressure within said chamber 123 may be registered on said gauge 140 and this pressure will be the same as that within the bore 131, the pipe 96 and in the lower portion of the valve body 99 beneath the partition 139. The valve body 99 of the motor valve B and the valve body 103 of the release valve C are similar to the valve body 94 of the regulator valve A and will not be described in detail. In fact, the entire construction of these valves are very similar with a few changes being made in the valve stems and the replaceable seat bushings.

The valve stem 141 of the motor valve B is

solid and has an enlarged foot piece or is upset to form a valve member 142 on its lower end and, as will be seen in Figure 4, this pin extends through a replaceable seat bushing 143 threaded into the partition 139. This bushing 143 is provided with an axial bore 144, on the lower end of which is formed a ground, tapered seat to coact with the valve face 145 to open and close the passageway 146, which permits or terminates the flow of fluid from the pipe 96 to the pipe 100 through said valve body 99. The upper end of this stem 141 has a piston 146 fastened thereon and this piston and the valve stem are clamped to a diaphragm disk 147 by a nut 148, the same as the regulator valve A.

The diaphragm cap 149 of the motor valve B, which is similar to the diaphragm cap 118 of the regulator valve A, forms a diaphragm actuating chamber 177 and said cap 149 has a pipe 150 connected thereto which extends to a T 151. The lower end or leg of this T 151 is connected into the diaphragm cap 152, which is similar to the diaphragm caps 118 and 149, on the upper end of the release valve C and a diaphragm actuating chamber 176 is formed therein above a diaphragm disk 154. The valve stem 153 of the release valve C is also solid and is connected to the diaphragm 154, the same as the valves A and B. The lower end of this valve stem 153 is beveled or tapered to form a valve tip or face 155. The valve body 103 is provided with a transverse partition 156 which has an internally screw-threaded port 157 extending therethrough for receiving a replaceable seat bushing 158. This bushing has an axial bore or passageway 159, the upper end of which is formed with a ground seat for co-acting with the valve face 155 to open and close the passageway 159.

The valve body 99 has an internally screw-threaded box 160 on its lower end in which a drain or clean-out plug 161 is threaded. The valve body 103 has a similar internally screw-threaded box 162 for receiving the threaded pin of a pipe 163 and this valve body also has an internally screw-threaded box 164, diametrically opposite the box 162, for receiving a pet cock 165 which leads or is vented to the atmosphere.

This pipe 163 leads out of the housing 88 to the lower end of an actuating cylinder 166, which has a reciprocating piston 167 slidably mounted therein. This piston may be suitably suspended from the usual stub derrick 168, or the usual "gin pole" (not shown), or any other support desired. The piston 167 has a piston rod 169 depending therefrom and extending out of the lower end of the cylinder 166 and on the lower end of this piston rod 169 is mounted a suitable wire line clamp 170. This cylinder 166, piston 167, piston rod 169 and wire line clamp 170 are similar to those shown in some of my other Patents Nos. 2,171,478; 2,171,812; and 2,202,462; and may be of any desired structure.

The clamp 170 is fastened to the wire line 83 so that when the piston 167 is reciprocated in the cylinder, the wire line 83 will be moved therewith, whereby the actuating bar 81 and weight bar 85 will be moved in said tubing string 24 accordingly. In Figure 1, it will be seen that the slack end of said wire line 83 may extend up over the sheaves of a crown block 171 on the upper end of the derrick 168, and then down to a suitable drum or hoist (not shown), as is the usual practice. It is preferred that the cylinder 166 be suspended co-axially with the tubing 24 of the well, thus assuring a vertical alignment.

In operation, the pressure fluid from the field line pipe 22 through the pipe 91 into the valve body 94. This pressure fluid will flow through the port 138 into the valve body above the partition 104, through the pipe 96, into valve body 99 beneath the partition 139, through the bore 131 of the piston rod 124, into said diaphragm actuating chamber 123 on top of said diaphragm 122; all of which serves as a pressure fluid reservoir for supplying pressure fluid at a reduced pressure. When the valve face 145 of the motor valve B is opened, pressure fluid will be drawn from the valve body 99 beneath the partition 139, the pipe 96, the valve body 94 above the partition 104, the bore 131 of the valve stem 124 and the diaphragm actuating chamber 123. This reduction of pressure fluid in the reservoir will permit the spring 130 to lift the valve stem 124 and open the port 138 for replenishing the reservoir. The well casing 20 extends down into the well forming an annulus or storage chamber for a pressure lifting fluid, as is the usual practice, and a string of tubing 24 is mounted within said casing (Figures 1 and 2). This string of tubing contains a plurality of flow valves 30 although there are various types of valves that may be used in conjunction with one of my valves shown and it is possible to use any of the flow valves illustrated in any of my patents Nos. Re. 21,199; 2,164,469; 2,171,480; 2,171,812; 2,202,462; and 2,204,817, or other sub-well equipment. I prefer for the purpose of illustration to show three of the flow valves, described in this application, mounted in said tubing string 24 and the spacing of these valves is determined in accordance with the conditions and circumstances surrounding a particular installation. Therefore, the number of valves and other types of flow valves or equipment used therewith is determined by the installation being made.

The actuating bar 81 and weight bar 85, on the lower end of the wire line 83 are lowered into said tubing and the movement of this wire line, at this time, is controlled by a hoist, or other suitable mechanism (not shown). The actuating bar is lowered into the uppermost flow valve 30, or whichever one it is desired to operate. This uppermost valve is usually set below the standing level of the well fluid in the tubing and casing and when said bar is suspended in said valve (Figure 5), the roller 80 is swung outwardly and the yoke 76 downwardly, which slides the sleeve 72 downwardly on the valve stem 60. If the column of fluid within the tubing is sufficiently high or long to exert a predetermined back pressure on the valve head 59, this back pressure, together with the tension of said spring 67, will force said valve stem 60 and valve head 59 downwardly and this admits pressure lifting fluid from the casing 20 through the perforations 51, into the chamber 50, through the port 57, into the housing 47, through the channel 46 and recess 87 and into the valve body 30. Of course, with the bar 81 in the bore 42 of said valve body, the lifting fluid will flow through the channel 46, the recess 87 and into the ducts 44, as well as the bore 42, and will lift this cut off portion of the column of well fluid upwardly and out of said tubing 24 and through the flow line 26.

When this upwardly flowing column of well fluid exerts a sufficient pressure in the pipe 26, this pressure will be transmitted through a pipe 174 that is connected at one end to the flow line

26 and extends to the upper or remaining leg of the T 151, which is connected to the diaphragm cap 152 of said release valve C. This exerted pressure will be transmitted from the pipe 174, through the T 151, into the diaphragm actuating chamber 176 of the diaphragm cap 152, onto the diaphragm 154 of said release valve C and through the pipe 150 into the diaphragm actuating chamber 177 of said diaphragm cap 149, on top of said diaphragm 147 of said motor valve B. It will be noticed in Figure 4, that the spring 175 of said valve C is set to exert less tension than the spring 173 of the valve B. Also, the valve head 142 has to open against a certain pressure while the valve face 155 has to close against only the atmosphere pressure, so that even if the tensions of the springs 173 and 175 should be substantially the same, the valve C would still close before the valve B would open. Therefore, the pressure building up in the diaphragm actuating chambers 176 and 177 will move the valve stem 153 downwardly before the valve stem 141 is moved downwardly. This brings the valve face 155 into engagement with the seat of said bore 159 of the removable bushing 158, closing off the upper portion of the valve body 103, so that when the pressure in the diaphragm chamber 177 increases sufficiently to move the valve stem 141 downwardly against the tension of the spring 173 and the pressure in said valve body 99 beneath the partition 139, the valve face 145 is moved away from the seat at the lower end of the bore 144 of the bushing 143. The release valve C will have been already seated and closed so that the pressure fluid admitted from the pipe 96 by the valve member 145 will flow through the pipe 100 and into the pipe 163, where it is led to the cylinder 166 beneath the piston 167.

This pressure fluid will lift this piston and the piston rod 169, as well as the wire line 83, which moves the actuating bar 81 out of said bore 42, or at least, to its position shown in Figure 7. This will release the roller 80 and permit the spring 74 to lift said sleeve 72 and said yoke 76 and to swing said lever 77 and said roller 80 inwardly. The spring 74 will move said sleeve 72, said stop collar 69, said valve stem 60 and said valve head 59 upwardly, whereby said valve head 59 is closed against its seat 58 and the admission of lifting fluid to said tubing is terminated.

The closing of the valve head 59 terminates further admission of lifting fluid and the pressure within said tubing string 24 and flow line 26 will be reduced. Naturally, the pressure in said pipe 174, said diaphragm actuating chambers 176 and 177, said pipe 150, said T 151 and said diaphragm caps 149 and 152 will be reduced also. When this occurs, the valve member 145 will close and engage its seat in the motor valve B first, which terminates the additional admission of pressure fluid from the pipe 96. As this pressure continues to be reduced, the valve stem 153 will rise and this opens the passageway 159 to permit the pressure fluid within the valve body 103, the pipe 100, the pipe 163 and the cylinder 166 beneath the piston 167 to flow through said passageway 159 of said bushing 158 and said valve body 103, above said partition 156, out through said pet cock 165, where it is vented or bled to the atmosphere. As this trapped pressure is bled, the piston 167 will lower to its original position, which will return the actuating bar 81 to its original position (Fig-

ure 5). The well may be operated from this particular valve, or the actuating bar may be dropped to a lower valve, where the above operation is again carried out.

It will be seen that a semi-automatic valve is thus had and a control unit therefor, which will admit lifting fluid only when there is a sufficient column of well fluid to be lifted and that the admission of lifting fluid is terminated as soon as the lifted charge or slug has sufficient lifting fluid therebeneath to carry it through the flow line 26 to a storage tank, or any other suitable disposal (not shown).

It is pointed out that the spring 14 is much stronger than the spring 61, so that whenever the bar releases the roller 80, said spring 14 will lift the sleeve 72, swinging the lever 11 and said roller inwardly. The upper end of said sleeve will already be in engagement with the underside of said stop collar 69 (when said valve head 59 is opened, said stop collar will drop down on said sleeve) and the valve stem 60 will be lifted and the valve head 59 seated on its seat 58 to close the port 57 and shut off the admission of additional lifting fluid from said casing 20 into said tubing 24.

Attention is called to the fact that the spring 67 is set for a predetermined compression in order that a definite, known pressure differential may be had between the column of well fluid in the tubing and the lifting fluid in the casing. Therefore, the weight or pressure of the column of well fluid plus the compression of the spring 67 is the operating pressure to open the valve 30, when said bar is in said valve to unlock or release the same for actuation. When the pressure of the column of well fluid plus the compression of said spring 67 becomes greater than the pressure of the lifting fluid in the casing, the valve head 59 will be moved downwardly away from its seat 58 to open the port 57, whereby lifting fluid will be admitted to expell said column of well fluid. Thus, by using different springs 67 of different compressions, various differentials or lengths of columns of well fluid may be had and various adjustments may thus be obtained in accordance with the well conditions encountered.

A further adjustment or control of the production from the well may be obtained by varying the pressure of the lifting fluid in the casing. The spring 67 when installed, is known to have a predetermined compression to set up a certain pressure differential and by increasing or decreasing the pressure of the lifting fluid, a number of results may be had. These are: first, the quantity or length of the column of well fluid may be controlled so that a greater or smaller amount of well fluid will accumulate before the valve head 59 is opened; second, the velocity or speed of flow up the tubing of the cut off column or "slug" of well fluid may be regulated; third, the intervals at which the slugs of well fluid are lifted may be spaced farther apart or closer together; and fourth, where wells produce fluid slowly or not very high in the tubing, termed low fluid level wells, this low fluid level or short column of well fluid may be handled or lifted readily and more economically by reducing the lifting fluid pressure in the casing. These four results usually will handle any producing or well condition presented, either with or without changing the compression of the spring 67. However, in some instances the adjustment of said spring compression may be required in

addition to varying the lifting fluid pressure in the casing.

The surface control mechanism may also be regulated to handle different flow conditions presented in various installations. The spring 173 of the motor valve B is usually set with a greater compression than the spring 175 of the release valve C, although in some instances the compressions of the springs 173 and 175 may be substantially the same and due to the difference in area between the valve head 142 and valve face 155, the motor valve B still will require a greater pressure in the diaphragm actuating chamber 171 to open said valve than the release valve C will require in the diaphragm actuating chamber 176. However, the compressions of these springs may be regulated to handle various conditions, as may be required, or to obtain the most economical operation. The varying or changing of the compressions of said springs 173 and 175 will control the closing of said release valve C and the opening of said motor valve B, as well as the closing of said valve B and the opening of said valve C.

The lengths of the slugs or column of well fluids, that is a long or a short slug, as well as a light or a heavy slug, would require different settings of said springs 173 and 175. Further, the compressions of said springs depend on the weight of a slug in accordance with the constituents thereof, as oil is lighter than fresh water and has a greater cohesion, while salt water is heavier than fresh water and its cohesion is less. The length of a flow line from the well to a storage tank also determines the setting of the springs 173 and 175, because a long flow line would require a higher opening or operating pressure in the diaphragm actuating chamber 171 of the motor valve B and a lower pressure in the diaphragm actuating chamber 176 of said release valve C, than would a short flow line. The reason being that for a long flow line, more lifting fluid would have to be admitted and the compression of the spring 173 of the motor valve B would have to be increased to hold the fluid inlet valve 30 in the tubing string open for a longer period of time. Also, the compression of the spring 175 of said release valve C would have to be decreased to prevent the releasing or unlocking of said inlet valve 30 for automatic operation, before the pressure in the tubing has bled down or been reduced to a point or degree that this pressure in the tubing, together with the compression of the spring 61, would not be sufficient to open the valve head 59 when said bar 81 is dropped back into the bore 42 of said valve body 30 to unlock or release said valve. A short flow line would require a shorter period of admittance of lifting fluid and less compression of the spring 173 of said motor valve B and a greater compression may thus be placed on the spring 175 of said release valve C to release said inlet valve 30 for automatic operation earlier. Further, the spring 173 of said motor valve B may have about the usual setting to produce substantially a normal compression, while the spring 175 of said release valve C may have a much greater setting to unlock the fluid inlet valve 30 early, or very little compression on said spring 175 to unlock said inlet valve 30 when the pressure in the tubing is only a few pounds.

In Figures 13, 15, 16 and 17, I have shown a slightly modified form of control mechanism and actuating bar in which the positions of the motor valve B and release valve C have been inverted

and their functions altered. These valves operate in the same manner as that shown in Figure 4, and the purpose for the transfer of these two valves is that the usual type of weight bar, or only the weight bar 85 shown in Figures 3, 5, 6 and 7, may be used without the actuating bar 81. These valves operate in the same order and the same numbers have been carried over. The valve C is still open in its normal position and is the first to close and the valve B is normally closed and is opened after said valve C has closed, and is closed upon the reduction of the pressure in said diaphragm actuating chambers 176 and 177, before the valve C is opened.

It will be seen in Figure 13, which is the normal position of these valves, that the pressure fluid may flow from the pipes 91 and 96 into the pipes 100 and 163 to hold the piston 167 in the upper end of the cylinder 166 (Figure 15). This will hold the upper end of the weight bar 85 in the valve body 30, as is shown in Figures 15 and 16, which in this modified form becomes an actuating bar as well as a weight bar. In this position, of course, the roller 80 and the lever 71 are swung outwardly and the yoke 76 and the sleeve 72 are slid downwardly, so as to unlock or release the valve head 59, so that when a sufficient column of well fluid is built up above the valve 30 to exert a weight or back pressure on said valve head 59, which together with the compression of the spring 67 will open said valve head to admit lifting fluid through the perforations 51 and chamber 50 into said valve body 30 to cut off and lift the well fluid thereabove, the same as in the other form of this invention.

When a sufficient back pressure is exerted through the pipes 174 and 150, the valve C is closed first, cutting off the admission of pressure fluid from the pipe 96. Then the valve B is opened to permit this pressure fluid trapped in the pipes 100 and 163 and in the cylinder 166 to be vented to the atmosphere through the pet cock 165, which lowers the piston 167, the wire line 83 and the weight bar 85 on the lower end thereof. This lowering will permit the weight bar 85 to drop down out of the bore 42 of the valve body 30, as shown in Figure 17. As the bar is lowered out of the inlet valve 30, the roller 80 and the lever 71 will swing inwardly and the yoke 76 and the sleeve 72 will move upwardly, due to the compression of said spring 74, whereby the valve head 59 will be closed and further admission of lifting fluid will be terminated. As the pressure is reduced in said tubing 24, said flow line 26, said pipes 174 and 150, said T 151 and said diaphragm actuating chambers 176 and 177, the valve member 145 of said valve B will be closed in accordance with the setting of the spring 173. Then, depending on the setting of the spring 175, the valve face 155 of said valve C will be opened, whereby pressure fluid may now flow from the pipe 96, into the valve body 103, through the pipe 139, through the pipe 163 and into said cylinder 166 beneath the piston 167. This pressure fluid will again lift said piston 167 to the upper end of said cylinder 166, as shown in Figure 15, and this will pull the weight bar 85 up into the valve body 30, as shown in Figure 16.

The reason for this arrangement is that a one piece actuating and weight bar may be used, such as is common teaching in a number of my patents, instead of having a divided bar, the upper bar of which serves as an actuating bar. The same purposes, results and functions are obtained

with this form of the invention and it is merely a modified operation to handle certain well conditions, or installations which already may be made, or with the equipment on hand. This form of the invention may be adjusted or regulated the same as the other form.

There are various other changes, alterations and modifications that may be made in the size, shape and arrangement of the herein-described elements, within the scope of the invention and the appended claims.

What I claim and desire to secure by Letters Patent is:

1. In a well flowing apparatus wherein a well casing is provided with a supply of lifting fluid and a well tubing string is mounted therein, the combination of, a lifting fluid inlet valve mounted in the tubing for admitting well and lifting fluid from the casing to the tubing to flow well fluid through said tubing, means controlled from the surface of the well for locking said valve against operation or unlocking said valve where it may be operated, said valve having elements responsive to pressure differentials between the well fluid in the tubing string and the lifting fluid in the casing and operable when said valve is unlocked, actuating means on the surface of the well for actuating said surface operated means, a flow conduit extending to said actuating means for supplying a pressure fluid thereto to operate said actuating means, surface control means connected to said flow conduit for controlling the flow of a pressure fluid through said conduit to control the operation of said actuating means, valve means in said surface control means for controlling the flow of an actuating fluid through said flow conduit and said surface control means to said actuating means, and valve means in said surface control means connected to the flow conduit beyond the first valve means for venting said flow conduit when said first valve means has terminated the flow of fluid through said conduit, and means whereby both of said valves are operated by the pressure of the flowing fluid in said tubing.

2. In a well flowing apparatus wherein a well casing is provided with a supply of lifting fluid and a well tubing string is mounted therein, the combination of, a lifting fluid inlet valve mounted in the tubing for admitting well and lifting fluid from the casing to the tubing to flow well fluid through said tubing, means controlled from the surface of the well for locking said valve against operation or unlocking said valve where it may be operated, said valve having elements responsive to pressure differentials between the well fluid in the tubing string and the lifting fluid in the casing and operable when said valve is unlocked, actuating means on the surface of the well for actuating said surface operated means, a flow conduit extending to said actuating means for supplying a pressure fluid thereto to operate said actuating means, valve means connected in the conduit for controlling the flow through the conduit, valve means connected to the flow conduit in addition to the first valve means for venting said flow conduit when said first valve means has terminated the flow of fluid through said conduit, and means connected to said flow conduit ahead of said first valve means for reducing the pressure of the fluid flowing through the conduit therefrom, and means whereby said first and second valve means are actuated by the pressure of the flowing fluid in said tubing.

3. In a well flowing apparatus wherein a well casing is provided with a supply of lifting fluid and a well tubing string is mounted therein, the combination of, a lifting fluid inlet valve mounted in the tubing for admitting well and lifting fluid from the casing to the tubing to flow well fluid through said tubing, means controlled from the surface of the well for locking said valve against operation or unlocking said valve where it may be operated, said valve having elements responsive to pressure differentials between the well fluid in the tubing string and the lifting fluid in the casing and operable when said valve is unlocked, actuating means on the surface of the well for actuating said surface operated means, a flow conduit extending to said actuating means for supplying a pressure fluid thereto to operate said actuating means, valve means connected in the conduit for controlling the flow through the conduit, valve means connected to the flow conduit in addition to the first valve means for venting said flow conduit when said first valve means has terminated the flow of fluid through said conduit, and means connected to said flow conduit ahead of said first valve means for reducing the pressure of the fluid flowing through the conduit therefrom, and means whereby said first and second valve means are actuated by the pressure of the flowing fluid in said tubing, said first and second valve means being adapted to be regulated so that their actuation by the flowing well fluid may be controlled.

4. In a well flowing apparatus wherein a well casing is provided with a supply of lifting fluid and a well tubing string is mounted therein, the combination of, a lifting fluid inlet valve mounted in the tubing for admitting well and lifting fluid from the casing to the tubing to flow well fluid through said tubing, means controlled from the surface of the well for locking said valve against operation or unlocking said valve where it may be operated, said valve having elements responsive to pressure differentials between the well fluid in the tubing string and the lifting fluid in the casing and operable when said valve is unlocked, actuating means on the surface of the well for actuating said surface operated means, a flow conduit extending to said actuating means for supplying a pressure fluid thereto to operate said actuating means, valve means connected in the conduit for controlling the flow through the conduit, and valve means connected to the flow conduit in addition to the first valve means for venting said flow conduit when said first valve means has terminated the flow of fluid through said conduit, and means whereby said first and second valve means may be regulated whereby their actuation by a fluid auxiliary to the fluid flowing through the conduit may be controlled to handle various well conditions encountered.

5. A control unit for flowing fluids wherein a well casing is provided with a supply of lifting fluid and a well tubing is mounted therein and an inlet valve is connected to the tubing for admitting fluid into said tubing and an actuator for operating the inlet valve including, actuating means for controlling the operation of the actuator to operate the inlet valve to control flow of fluid in the tubing, a fluid conduit connected to the actuating means, a feed controlling valve connected to said conduit for controlling the flow of fluid through said conduit, and a release valve connected to said conduit for venting the conduit or permitting the fluid to flow to the actuating means, and means whereby said feed and

release valves are actuated by the pressure of the flowing fluids in the well tubing.

6. A control unit for flowing fluids wherein a well casing is provided with a supply of lifting fluid and a well tubing is mounted therein and an inlet valve is connected to the tubing for admitting fluid into said tubing and an actuator for operating the inlet valve including, actuating means for controlling the operation of the actuator to operate the inlet valve to control flow of fluid in the tubing, a fluid conduit connected to the actuating means, a fluid supply valve connected to said conduit for controlling flow of fluid to said conduit, a feed valve connected to said conduit for controlling the flow of fluid through said conduit, and a release valve connected to said conduit for venting the conduit or permitting the fluid to flow to said actuating means, and means whereby said feed and release valves are actuated by the pressure of the flowing fluids in the well tubing.

7. A control unit for flowing fluids wherein a well casing is provided with a supply of lifting fluid and a well tubing is mounted therein and an inlet valve is connected to the tubing for admitting fluid into said tubing and an actuator for operating the inlet valve including, actuating means for controlling the operation of the actuator to operate the inlet valve to control flow of fluid in the tubing, a fluid conduit connected to the actuating means, means for controlling the flow of fluid to the conduit at a reduced pressure, a feed valve connected to said conduit for controlling the flow of fluid through said conduit, and a release valve connected to said conduit for venting the conduit or permitting the fluid to flow to said actuating means, and means whereby said feed and release valves are actuated by the pressure of the flowing fluids in the well tubing.

8. A control unit for flowing fluids wherein a fluid flow conductor is positioned in a well and an inlet valve is connected to the conductor for admitting fluid into said conductor and an actuator for operating the inlet valve including, a fluid feed conduit having an inlet and an outlet leading to actuating means, means for controlling the flow of fluid from the inlet to the conduit at a reduced pressure, a feed valve connected to said conduit for controlling the flow through said conduit, a vent connected to said conduit between the feed valve and the conduit outlet, and a release valve connected to said conduit for controlling the flow of fluid in said conduit to said outlet to said actuating means or to said vent for bleeding said actuating means, and means whereby said feed valve and said release valve are actuated by the pressure of the flowing fluids in the flow conductor.

9. In a well flowing apparatus wherein a well casing is provided with a supply of lifting fluid and a well tubing is mounted therein, the combination of, a lifting fluid inlet valve connected to the tubing for admitting fluid from the casing into said tubing, means controlled from the surface of the well for locking said valve against operation or unlocking said valve where it may be operated, said valve having elements responsive to pressure differentials between the well fluid in the tubing and the lifting fluid in the casing and operable when said valve is unlocked, actuating means on the surface of the well for actuating said surface controlled means, a flow conduit having an inlet and an outlet extending to said actuating means for supplying a pres-

sure fluid thereto to operate said actuating means, valve means for controlling the flow of pressure fluid from the inlet to the conduit at a reduced pressure, a feed valve connected to said conduit for controlling the flow through said conduit, a vent connected to said conduit between the feed valve and the conduit outlet, and a control valve connected to said conduit for controlling the flow of fluid in said conduit to said outlet to said actuating means or to said vent for bleeding said actuating means, and means whereby said feed valve and said control valve are actuated by the pressure of the flowing fluids in the tubing.

10. The system of flowing wells which includes, a well casing for providing a supply of lifting fluid, a well tubing in the casing for accumulating a quantity of well fluid and serving as a conductor for the well fluid, one or more lifting fluid inlet valves connected to the tubing, means for normally fastening the valve or valves against and releasing said valve or valves for operation by a pressure differential between the well fluid and the lifting fluid, means for providing a predetermined amount of mechanical energy which when combined with a hydrostatic pressure of a predetermined quantity of well fluid causes opening of said valve, said fastening and releasing means including resilient means for closing said valve or valves, said valves being constructed so that the opening thereof may be controlled by the varying of the pressure of the lifting fluid in the casing, means on the surface of the well for controlling the operation of the fastening and releasing means, means for controlling the opening period of the surface controlling means, means for controlling the closing period of the surface controlling means, and means whereby the pressure of the elevated well fluid is utilized to control both said opening controlling means and said closing controlling means, said opening and closing controlling means having adjusting means for controlling and independently regulating the opening and closing periods of the surface controlling means.

11. A control unit for flowing fluids wherein a well casing is provided with a supply of lifting fluid and a well tubing is mounted therein and an inlet valve is connected to the tubing for admitting fluid into said tubing and an actuator for operating the inlet valve including, actuating means for controlling the operation of the actuator to operate the inlet valve to control flow of fluid in the tubing, a fluid conduit connected to the actuating means, a feed controlling valve connected to said conduit for controlling the flow of fluid through said conduit, and a release valve connected to said conduit for venting the conduit or permitting the fluid to flow to the actuating means, and means whereby said feed and release valves are actuated by the pressure of the flowing fluids in the well tubing, said feed and release valves having adjusting means for controlling and independently regulating the opening and closing periods of said valves.

12. A control unit for flowing fluids wherein a well casing is provided with a supply of lifting fluid and a well tubing is mounted therein and an inlet valve is connected to the tubing for admitting fluid into said tubing and an actuator for operating the inlet valve including, actuating means for controlling the operation of the actuator to operate the inlet valve to control flow of fluid in the tubing, a fluid conduit connected to the actuating means, a fluid supply valve

connected to said conduit for controlling flow of fluid to said conduit, a feed valve connected to said conduit for controlling the flow of fluid through said conduit, and a release valve connected to said conduit for venting the conduit or permitting the fluid to flow to said actuating means, and means whereby said feed and release valves are actuated by the pressure of the flowing fluids in the well tubing, said feed and release valves having adjusting means for controlling and independently regulating the opening and closing periods of said valves.

13. A control unit for flowing fluids wherein a well casing is provided with a supply of lifting fluid and a well tubing is mounted therein and an inlet valve is connected to the tubing for admitting fluid into said tubing and an actuator for operating the inlet valve including, actuating means for controlling the operation of the actuator to operate the inlet valve to control flow of fluid in the tubing, a fluid conduit connected to the actuating means, means for controlling the flow of fluid to the conduit at a reduced pressure, a feed valve connected to said conduit for controlling the flow of fluid through said conduit, and a release valve connected to said conduit for venting the conduit or permitting the fluid to flow to said actuating means, and means whereby said feed and release valves are actuated by the pressure of the flowing fluids in the well tubing, said feed and release valves having adjusting means for controlling and independently regulating the opening and closing periods of said valves.

14. A control unit for flowing fluids wherein a fluid flow conductor is positioned in a well and an inlet valve is connected to the conductor for admitting fluid into said conductor and an actuator for operating the inlet valve including, a fluid feed conduit having an inlet and an outlet leading to actuating means, means for controlling the flow of fluid from the inlet to the conduit at a reduced pressure, a feed valve connected to said conduit for controlling the flow through said conduit, a vent connected to said conduit between the feed valve and the conduit outlet, and a release valve connected to said conduit for controlling the flow of fluid in said conduit to said outlet to said actuating means or to said vent for bleeding said actuating means, and means whereby said feed valve and said release valve are actuated by the pressure of the flowing fluids in the flow conductor, said feed and release valves having adjusting means for controlling and independently regulating the opening and closing periods of said valves.

15. In a well flowing apparatus wherein a well casing is provided with a supply of lifting fluid and a well tubing is mounted therein, the combination of, a lifting fluid inlet valve connected to the tubing for admitting fluid from the casing into said tubing, means controlled from the surface of the well for locking said valve against operation or unlocking said valve where it may be operated, said valve having elements responsive to pressure differentials between the well fluid in the tubing and the lifting fluid in the casing and operable when said valve is unlocked, actuating means on the surface of the well for actuating said surface controlled means, a flow conduit having an inlet and an outlet extending to said actuating means for supplying a pressure fluid thereto to operate said actuating means, valve means for controlling the flow of pressure fluid from the inlet to the conduit at a reduced

pressure, a feed valve connected to said conduit for controlling the flow through said conduit, a vent connected to said conduit between the feed valve and the conduit outlet, and a control valve connected to said conduit for controlling the flow of fluid in said conduit to said outlet to said actuating means or to said vent for bleeding said actuating means, and means whereby said feed valve and said control valve are actuated by the pressure of the flowing fluids in the tubing, said feed and release valves having adjusting means for controlling and independently regulating the opening and closing periods of said valves.

16. The system of flowing wells which includes, a well casing for providing a supply of lifting fluid, a well tubing in the casing for accumulating a quantity of well fluid and serving as a conductor for the well fluid, one or more lifting fluid inlet valves connected to the tubing, means for normally fastening the valve or valves against and releasing said valve or valves for operation by a pressure differential between the well fluid and the lifting fluid, means for providing a predetermined amount of mechanical energy which when combined with a hydrostatic pressure of a predetermined quantity of well fluid causes opening of said valve or valves, said fastening means including resilient means for closing said valve, said valves being adapted so that the opening thereof may be controlled by the varying of the pressure of the lifting fluid in the casing, means on the surface of the well for controlling the operation of the fastening and releasing means, means on the surface of the well to control the flow of a pressure fluid to operate for a period said surface controlling means, means on the surface of the well to control the flow of a pressure fluid to discontinue the operation of said surface controlling means, and means whereby both of said surface flow control means are actuated by the flowing well fluids in the tubing and having adjusting means for controlling and independently regulating the operating periods of said means.

17. In a well flowing apparatus wherein a well casing is provided with a supply of lifting fluid and a well tubing string is mounted therein, the combination of, a plurality of lifting fluid inlet valves mounted in the tubing for admitting lifting fluid from the casing to the tubing, said valves adapted to be selectively and intermittently operated, means controlled from the top of the well for bringing about the locking of said valves, said means also adapted to unlock said valves, said valves having elements which are responsive to pressure differentials between the well fluid and the lifting fluid and these elements are operable when said valves are unlocked, surface control means operated by a pressure fluid for actuating said surface operated means, a flow conduit connected to the surface control means for conveying the actuating pressure fluid thereto, valve means connected to the conduit for controlling the flow through said conduit, and a release valve connected to said conduit for controlling the flow of pressure fluid in said conduit to said surface control means or venting the pressure fluid from said surface control means, and means whereby said valve means and release valve are actuated by the pressure of the flowing fluids in the tubing.

18. In a well flowing apparatus wherein a well casing is provided with a supply of lifting fluid and a well tubing string is mounted therein, the combination of, a plurality of lifting fluid inlet

valves mounted in the tubing for admitting lifting fluid from the casing to the tubing, said valves adapted to be selectively and intermittently operated, means controlled from the top of the well for bringing about the locking of said valves, said means also adapted to unlock said valves, said valves having elements which are responsive to pressure differentials between the well fluid and the lifting fluid and these elements are operable when said valves are unlocked, surface control means operated by a pressure fluid for actuating said surface operated means, a flow conduit connected to the surface control means for conveying the actuating pressure fluid thereto, valve means connected to the conduit for controlling the flow through said conduit, and a release valve connected to said conduit for controlling the flow of pressure fluid in said conduit to said surface control means or venting the pressure fluid from said surface control means, and means whereby said valve means and release valve are actuated by the pressure of the flowing fluids in the tubing, said valve means and release valve having adjusting means for controlling and independently regulating the opening and closing periods thereof.

19. In a well flowing apparatus wherein a well casing is provided with a supply of lifting fluid and a well tubing string is mounted therein, the combination of, a plurality of lifting fluid inlet valves mounted in the tubing for admitting lifting fluid from the casing to the tubing, said valves adapted to be selectively and intermittently operated, means controlled from the top of the well for bringing about the locking of said valves, said means also adapted to unlock said valves, said valves having elements which are responsive to pressure differentials between the well fluid and the lifting fluid and these elements are operable when said valves are unlocked, surface control means operated by a pressure fluid for actuating said surface operated means, a flow conduit connected to the surface control means for conveying the actuating pressure fluid thereto, means for controlling the flow of fluid to the conduit at a reduced pressure, valve means connected to the conduit for controlling the flow through said conduit, and a release valve connected to said conduit for controlling the flow of pressure fluid in said conduit to said surface control means or venting the pressure fluid from said surface control means, and means whereby said valve means and release valve are actuated by the pressure of the flowing fluids in the tubing.

20. In a well flowing apparatus wherein a well casing is provided with a supply of lifting fluid and a well tubing string is mounted therein, the combination of, a plurality of lifting fluid inlet valves mounted in the tubing for admitting lifting fluid from the casing to the tubing, said valves adapted to be selectively and intermittently operated, means controlled from the top of the well for bringing about the locking of said valves, said means also adapted to unlock said valves, said valves having elements which are responsive to pressure differentials between the well fluid and the lifting fluid and these elements are operable when said valves are unlocked, surface control means operated by a pressure fluid for actuating said surface operated means, a flow conduit connected to the surface control means for conveying the actuating pressure fluid thereto, means for controlling the flow of fluid to the conduit for controlling the flow through said

conduit, and a release valve connected to said conduit for controlling the flow of pressure fluid in said conduit to said surface control means or venting the pressure fluid from said surface control means, and means whereby said valve means and release valve are actuated by the pressure of the flowing fluids in the tubing, said valve means and release valve having adjusting means for controlling and independently regulating the opening and closing periods thereof.

21. In a well flowing apparatus wherein a well casing is provided with a supply of lifting fluid and a well tubing is mounted therein, the combination of, a lifting fluid inlet valve connected to the tubing for admitting well and lifting fluid from the casing to the tubing to flow well fluid through said tubing, means controlled from the surface of the well for locking said valve against operation or unlocking said valve where it may be operated, said valve having elements responsive to pressure differentials between the well fluid in the tubing and the lifting fluid in the casing and operable when said valve is unlocked, actuating means on the surface of the well for actuating said surface operated means, a flow conduit extending to said actuating means for supplying a pressure fluid thereto to operate said actuating means, surface control means connected to said flow conduit for controlling the flow of a pressure fluid through said conduit to control the operation of said actuating means, valve means in said surface control means for controlling the flow through the surface control means, and valve means in said surface control means for controlling the flow to said actuating means to operate said actuating means or for releasing the fluid from said actuating means to return said actuating means after the same has been operated, and means whereby both of said valve means are actuated by the pressure of the flowing fluids in said tubing.

22. In a well flowing apparatus wherein a well casing is provided with a supply of lifting fluid and a well tubing is mounted therein, the combination of, a lifting fluid inlet valve connected to the tubing for admitting well and lifting fluid from the casing to the tubing to flow well fluid through said tubing, means controlled from the surface of the well for locking said valve against operation or unlocking said valve where it may be operated, said valve having elements responsive to pressure differentials between the well fluid in the tubing and the lifting fluid in the casing and operable when said valve is unlocked, actuating means on the surface of the well for actuating said surface operated means, a flow conduit extending to said actuating means for supplying a pressure fluid thereto to operate said actuating means, surface control means connected to said flow conduit for controlling the flow of a pressure fluid through said conduit to control the operation of said actuating means, valve means in said surface control means for controlling the flow through the surface control means, and valve means in said surface control means for controlling the flow to said actuating means to operate said actuating means or for releasing the fluid from said actuating means to return said actuating means after the same has been operated, and means whereby both of said valve means are actuated by the pressure of the flowing fluids in said tubing, said valve means having adjusting means for controlling and independently regulating the opened and closed periods of said valve means.

23. In a well flowing apparatus wherein a well casing is provided with a supply of lifting fluid and a well tubing is mounted therein, the combination of, a lifting fluid inlet valve connected to the tubing for admitting well and lifting fluid from the casing to the tubing to flow well fluid through said tubing, means controlled from the surface of the well for locking said valve against operation or unlocking said valve where it may be operated, said valve having elements responsive to pressure differentials between the well fluid in the tubing and the lifting fluid in the casing and operable when said valve is unlocked, actuating means on the surface of the well for actuating said surface operated means, a flow conduit extending to said actuating means for supplying a pressure fluid thereto to operate said actuating means, surface control means connected to said flow conduit for controlling the flow of a pressure fluid through said conduit to control the operation of said actuating means, valve means in said surface control means for controlling the flow through the surface control means, and valve means in said surface control means for controlling the flow to said actuating means to operate said actuating means or for releasing the fluid from said actuating means to return said actuating means after the same has been operated, and means whereby both of said valve means are actuated by the pressure of the flowing fluids in said tubing.

24. In a well flowing apparatus wherein a well casing is provided with a supply of lifting fluid and a well tubing is mounted therein, the combination of, a lifting fluid inlet valve mounted in the tubing for admitting well and lifting fluid from the casing to the tubing to flow well fluid through said tubing, means controlled from the surface of the well for locking said valve against operation or unlocking said valve where it may be operated, said valve having elements responsive to pressure differentials between the well fluid in the tubing and the lifting fluid in the casing and operable when said valve is unlocked, actuating means on the surface of the well for actuating said surface operated means, a flow conduit extending to said actuating means for supplying a pressure fluid thereto to operate said actuating means, valve means connected in the conduit for controlling the flow through the conduit, valve means connected to the flow conduit in addition to the first valve means for venting said flow conduit when said first valve means has terminated the flow of fluid through said conduit, and means whereby said first and second valve means are actuated by the pressure of the flowing fluids in said tubing.

25. In a well flowing apparatus wherein a well casing is provided with a supply of lifting fluid and a well tubing is mounted therein, the combination of, a lifting fluid inlet valve mounted in the tubing for admitting well and lifting fluid from the casing to the tubing to flow well fluid through said tubing, means controlled from the surface of the well for locking said valve against operation or unlocking said valve where it may be operated, said valve having elements responsive to pressure differentials between the well fluid in the tubing and the lifting fluid in the casing and operable when said valve is unlocked, actuating means on the surface of the well for actuating said surface operated means, a flow conduit extending to said actuating means for supplying a pressure fluid thereto to operate said actuating means, valve means connected in the

conduit for controlling the flow through the conduit, valve means connected to the flow conduit in addition to the first valve means for venting said flow conduit when said first valve means has terminated the flow through said conduit, means whereby said first and second valve means

are actuated by the pressure of the flowing fluids in said tubing, and means connected to said flow conduit ahead of said first valve means for reducing the pressure of the fluid flowing through the conduit therefrom.
